UNITED STATES PATENT OFFICE

2,044,683

CABLE CUTTER

Henry Gustafson, Astoria, Oreg.

Application October 22, 1935, Serial No. 46,235

7 Claims. (Cl. 164—47)

This invention relates to a cable cutter and has for its object to provide, in a manner as hereinafter set forth, a device of the class referred to for overcoming, when cutting a cable, the long, hard, inconvenient, cumbersome and awkward method now generally employed wherein a double bitted ax or cold chisel is employed.

A further object of the invention is to provide, in a manner as hereinafter set forth, a cable cutter so constructed that, when operated it will provide for expeditiously cutting a cable with a clean square cut with the omission of protruding strands or wires.

Further objects of the invention are to provide, in a manner as hereinafter set forth, a cutter for the purpose referred to which is simple in its construction and arrangement, strong, durable, compact, readily assembled, conveniently operated, positive in action, thoroughly efficient for the use intended thereby, and inexpensive to manufacture.

With the foregoing and other objects which may hereinafter appear, the invention consists of the novel construction, combination and arrangement of parts as will be more specifically described and as are illustrated in the accompanying drawing wherein is shown an embodiment of the invention, but it is to be understood that changes, variations and modifications may be resorted to which fall within the scope of the invention as claimed.

In the drawing:

Figure 1 is a vertical sectional view of the cutter showing the adaptation thereof with respect to a cable to be cut,

Figure 2 is a section on line 2—2, Figure 1,

Figure 3 is a section on line 3—3, Figure 1, and

Figure 4 is a perspective view of the invertible anvil element of the cutter.

The cutter includes a metallic stand 5 formed of a part providing a base 6, a part constituting an anvil support 7 integral with the upper face of base 6, and a part forming a tool guide 8 which has a portion 9 integral with the upwardly extending rear portion 10 of the top of support 7 and a portion 11 overhanging in spaced relation the portion 12 of support 7 forwardly of the upstanding rear portion 10.

The base 6 is of rectangular contour and of the desired thickness. The width and breadth of the support 7 is less than that of base 6. The support 7 is integral with the upper face of base 6 at the longitudinal median of the latter and has its front, rear and sides spaced from the edges of

base 6. The support and guide 7, 8, respectively, are of the same thickness.

The top of support 7 is formed with a square groove 13, a square socket 14 and an opening 15. The outer end of groove 13 is at the front of support 7. The side and bottom walls of the groove 13, at the inner end of the latter are flush with and merge into the side and bottom walls of socket 14. The opening 15 extends from the rear of support 7 and communicates at its forward end with socket 14 through the base of the latter. The support 7 includes a pair of spaced parallel upstanding front side cheeks 16, only one shown, having their inner faces forming flush continuations of the forward portions of the side walls of groove 13. The top edges 17 of the cheeks 16 are of compound curvature with the rear portions of said edges curving downwardly to and merging into the side walls of the groove. The intermediate portions 18 of the top edges of the side walls of the groove are of segmental contour.

The support 7 includes a pair of spaced parallel upstanding rear side cheeks 19 of substantially right angled triangular contour having their inner faces forming flush continuations of the side walls of groove 13. The forward edges 19a of the cheeks 19 are of arcuate contour. The top edges of the side cheeks 16 merge at their rear ends into the front ends of the segmental shaped intermediate portions 18 of the side walls of the groove 13. The lower ends of the forward edges of the cheeks 19 merge into the rear end of the segmental shaped intermediate portions 18 of the side walls of the groove. The rear parts of the top edges of cheeks 16 form forward continuations of the curve of the said intermediate portions 18. The forward edges of the cheeks 19 form rearward and upward continuations of the curve of the said intermediate portions 18.

The lower end of the portion 11 of tool guide 8 is of less height than the remaining portion of said guide. Parallel stretches of the lower end of portion 11 are of arcuate curvature, as at 20, which forms a continuation of the curve of the forward edges 19a of the cheeks 19. The portion 11 is formed with a rectangular passage 20 lengthwise thereof which extends from the upper to the lower ends thereof. The lower end of the front edge of portion 11 is rounded, as at 22, and which opposes in spaced relation the forward portions 18 of the top edges 17 of the cheeks 16.

The rounded lower end 22, the curved stretches of the lower end of portion 11, the curved forward edges 19a of the cheeks 19, the curved intermediate portions of the side wall of the groove 13,

the curved rear portion of the top edges 17 of the cheeks 16 and the curved forward portions of the top edges 17 of the cheeks 16 coact to provide a split circular opening 23 for conveniently arranging the cutter relative to the composite wire cable 23^a to be cut.

Removably mounted in and snugly engaging with the walls of the groove 13, as well as extending into and snugly engaging with the walls 10 of the socket 14, is a reversible anvil 24 in the form of a block of a cross-sectional contour corresponding to the shape of the groove and socket. The anvil 24 is formed with a series of flat side faces or sides 24^a for selectively supporting the cable 23^a. The cheeks 16 and 19 extend above the anvil 24. The intermediate portion of the selected side face or side of the anvil extends above the intermediate portions of the side walls of the groove and upon which is seated the cable. 20 The opening 15 is provided for the passage of a suitable instrument for forcing the anvil from the support 7. The cheeks 16, 19 act as a means for retaining the cable 23^a upon the exposed part of the selected side face or side of the anvil and 25 which in this instance would be the upper side face or side of the latter.

Slidably and snugly mounted in and of greater length than that of passage 21 is a cutter member or blade 25 of rectangular cross section. The 30 outer end of member 25 is formed with a centrally disposed flat outer edge part 26 for receiving blows from a suitable impacting element, not shown, for driving the member or blade 25 in an inward direction. The inner end of the member 25 has a cutting edge 27. The width of member 25 is materially greater than the diameter of the cable to be cut. The member 25 is formed lengthwise and centrally thereof with an elongated rectangular slot 28 having its inner end 35 wall 29 arranged between the transverse median of said member and the cutting edge 27. The inner end wall 29 of slot 28 is arranged in proximity to the inner side of the transverse median of member 25. The outer end wall 30 of slot 28 is arranged at a point substantially centrally with respect to the transverse median and edge part 26 of member 25. The slot 28 aligns with a pair of parallel slots 31, 32 formed in the side walls 33, 34 respectively, of the passage. 40 The outer end walls 35 of slots 31, 32 are arranged between the transverse medians and outer ends of the side walls 33, 34 of the passage. The inner end walls 36 of slots 31, 32 are arranged between the transverse medians and the 45 inner ends of the side walls 33, 34 of the passage.

The cutter includes a tightening element 37 for the cutting member or blade 25. The element 37 is of wedge-like form and comprises a tapered body 38 having its larger end formed with a centrally disposed squared edge part 39 for receiving blows from a suitable impacting element not shown. The smaller end 39^a of element 37 is pointed.

The stand 5 is provided with a handle 40 suitably connected therewith for conveniently carrying the cutter from one place to another. It is to be understood that the base 6 may, if desired, be provided with openings, not shown, for the passage of holdfast means, not shown, for anchoring the stand stationary.

The block which provides the anvil 24 is of soft or mild steel, because, if constructed of hard steel, it would dull the cutting edge of the cutter member or blade. As the block is square it permits of turning or inverting it when one of its sides or

side faces becomes impaired for the purpose of offering a non-impaired side or side face upon which the cable is positioned in the path of the member or blade 25. The latter is formed of tool steel, or its cutting end may be made of tool steel or some hardened steel that may stand use and wear. The element 37 is made of tough or spring steel to prevent its being notched, as notching, of course, would slow or hinder the cutting operation to be referred to.

The manner in which the cutter is operated will now be referred to. The cable is arranged in opening 23 and seated upon and transversely of the selected side or side face of the anvil. The cutter member or blade 25 is then inserted 15 through passage 21 with its cutting edge seated against the top of the cable. The element 37 is inserted through the slots 31, 32 and slot 28. After element 37 is positioned in the manner as stated, it is driven by a suitable implement so as 20 to go deeper into the slot 28 which tightens member or blade 25 against the cable. After the member or blade 25 has been tightened against the cable, the edge part 26 of said member or blade is successively impacted upon by a suitable 25 implement for intermittently forcing the member or blade through the cable to sever the latter. After each impact upon edge part 26, the element 37 is impacted upon for the purpose of tightening the cutting member or blade relative to the cable 30 to prevent any shifting of the cable on successive cutting strokes, as well as to provide for satisfactory operation of the cutting member or blade.

Often cables hang in the air, that is, run horizontally above ground. With this cutter, it is 35 possible and convenient to cut the cable without resting the base 6 on anything. In other words, the cutter may be worked above the ground. It is not necessary to drag the cable to the cutter, but the cutter may be brought to the cable and 40 used conveniently either on the ground or in the air above it.

The wedge 37, in close proximity to its end 39, is formed with an opening 40 for connecting therewith a removable means to prevent the 45 wedge from dropping out and, by way of example, the said means is shown in the form of a split ring 41.

What I claim is:

1. A cable cutter comprising a stand formed with a cable receiving opening and a cutting blade passage, an anvil removably mounted in said stand and extending into said opening for supporting the cable, an intermittently driven cutting blade positioned within and depending below the passage into said opening to sever the cable, an intermittently driven blade tightener extending through the stand and blade and engaging with the latter for tightening the blade against the cable after each cutting stroke of the 50 blade, and said stand provided with means for the passage of an implement to shift the anvil from the stand, said anvil being adjustable and formed with a series of selectable sides upon which the cable is mounted.

2. A cable cutter comprising a stand formed with a cable receiving opening and a cutting blade passage, an anvil removably mounted in said stand and extending into said opening for supporting the cable, an intermittently driven cutting blade positioned within and depending below the passage into said opening to sever the cable, and an intermittently driven blade tightener extending through the stand and blade and engaging with the latter for tightening the blade 55

against the cable after each cutting stroke of the blade, said stand being formed with a groove and a socket for receiving the anvil, said groove opening at one end at the front of the stand and at its other end into said socket, said anvil being adjustable and formed with a series of selectable sides upon which the cable is mounted.

5. A cable cutter comprising a stand formed with a cable receiving opening and a cutting blade passage, an anvil removably mounted in said stand and extending into said opening for supporting the cable, an intermittently driven cutting blade positioned within and depending below the passage into said opening to sever the cable, an intermittently driven blade tightener extending through the stand and blade and engaging with the latter for tightening the blade against the cable after each cutting stroke of the blade, said stand being formed with a groove and a socket for receiving the anvil, said groove opening at one end at the front of the stand and at its other end into said socket, and said stand being provided with means opening into said socket for the passage of an implement for shifting the anvil clear of the socket and groove, said anvil being adjustable and formed with a series of selectable sides upon which the cable is mounted.

6. A cable cutter comprising a stand formed with a cable receiving opening and a cutting blade passage, an anvil removably mounted in said stand and extending into said opening for supporting the cable, an intermittently driven cutting blade positioned within and depending below the passage into said opening to sever the cable, said stand being formed with aligning slots in opposed side walls of said passage, said blade being formed with a slot aligning with the said other slots, and an intermittently driven blade tightener extending through the said several slots and engaging with an end wall of the slot in the blade for tightening the latter against the cable after each cutting stroke of the blade.

7. A cable cutter comprising a stand formed with a cable receiving opening and a cutting blade passage, an anvil removably mounted in said stand and extending into said opening for supporting the cable, an intermittently driven cutting blade positioned within and depending below the passage into said opening to sever the cable, said stand being formed with aligning slots in opposed side walls of said passage, said blade being formed with a slot aligning with the said other slots, an intermittently driven blade tightener extending through the said several slots and engaging with an end wall of the slot in the blade for tightening the latter against the cable after each cutting stroke of the blade, said stand being formed with a groove and a socket for receiving the anvil, said groove opening at one end at the front of the stand and at its other end into said socket, and said stand being provided with means opening into said socket for the passage of an implement for shifting the anvil clear of the socket and groove.

8. A cable cutter comprising a stand formed with a slot aligning with the said other slots, and an intermittently driven blade tightener extending through the said several slots and engaging with an end wall of the slot in the blade for tightening the latter against the cable after each cutting stroke of the blade, said anvil being adjustable and formed with a series of selectable sides upon which the cable is mounted.

9. A cable cutter comprising a stand formed with a cable receiving opening and a cutting blade passage, an anvil removably mounted in said stand and extending into said opening for supporting the cable, an intermittently driven cutting blade positioned within and depending below the passage into said opening to sever the cable, said stand being formed with aligning slots in opposed side walls of said passage, said blade being formed with a slot aligning with the said other slots, an intermittently driven blade tightener extending through the said several slots and engaging with an end wall of the slot in the blade for tightening the latter against the cable after each cutting stroke of the blade, said anvil being adjustable and formed with a series of selectable sides upon which the cable is mounted, and said stand provided with means for the passage of an implement to shift the anvil from the stand.

10. A cable cutter comprising a stand formed with a cable receiving opening and a cutting blade passage, an anvil removably mounted in said stand and extending into said opening for supporting the cable, an intermittently driven cutting blade positioned within and depending below the passage into said opening to sever the cable, said stand being formed with aligning slots in opposed side walls of said passage, said blade being formed with a slot aligning with the said other slots, an intermittently driven blade tightener extending through the said several slots and engaging with an end wall of the slot in the blade for tightening the latter against the cable after each cutting stroke of the blade, said stand being formed with a groove and a socket for receiving the anvil, said groove opening at one end at the front of the stand and at its other end into said socket, and said stand being provided with means opening into said socket for the passage of an implement for shifting the anvil clear of the socket and groove.

HENRY GUSTAFSON.
